CLAIM

The ornamental design for a propane tank transport stabilizer, as shown and described.

DESCRIPTION

FIG. 1 is a perspective view of a propane tank transport stabilizer showing our new design, wherein a partial view of a propane tank is shown in broken lines for illustrative purposes only and forms no part of the claimed design;

FIG. 2 is a front view thereof;

FIG. 3 is a side view, the opposite side being a mirror image thereof;

FIG. 4 is a rear view thereof;

FIG. 5 is a top view thereof; and

FIG. 6 is a bottom view thereof; and,

FIG. 7 is a top perspective view with a portion cut away to illustrate the open interior.

1 Claim, 4 Drawing Sheets

FIG. 1

FIG. 2

FIG. 4

FIG. 3

FIG. 5

FIG. 6

FIG. 7
